ATTORNEY

UNITED STATES PATENT OFFICE.

PIERRE JOSEPH CHÉRON, OF NEW YORK, N. Y., ASSIGNOR TO FERDINAND FUCHS, HENRY FUCHS, AND FREDERICK FUCHS, OF JERSEY CITY, NEW JERSEY.

DESIGN FOR A BORDER FOR SILVERWARE.

SPECIFICATION forming part of Design No. 28,504, dated April 26, 1898.

Application filed December 8, 1897. Serial No. 661,207. Term of patent 3½ years.

To all whom it may concern:

Be it known that I, PIERRE JOSEPH CHÉRON, a citizen of the United States, residing at the city, county, and State of New York, have invented and produced a new and original Design for a Border for Silverware and Similar Articles, of which the following is a specification, reference being made to the accompanying drawing, forming part thereof.

As shown in the accompanying drawing, the leading feature of my design consists of the general configuration of the flower, stem, leaves, and tendrils of what is known as the "clover-plant," A being the clover-flower, B the stem, C and c the large and small leaves, respectively, and which are shown as of the four-leaved order, and D being the coiled

tendrils of the plant. These parts are disposed or arranged within a zone of substantially uniform width and in the order shown 20 in the drawing, so that the complete design constitutes a border or band. The work is repoussé, standing out in relief, and the stems and tendrils connecting the flowers and leaves form a continuous design. 25

I claim—

The design for a border for silverware and similar articles substantially as herein shown and described.

PIERRE JOSEPH CHÉRON.
